[57] CLAIM

The ornamental design for a firewood carrier or similar article, as shown and described.

DESCRIPTION

FIG. 1 is a perspective view of a firewood carrier or similar article showing my new design;

FIG. 2 is a plan view thereof;

FIG. 3 is a right side end view thereof;

FIG. 4 is a front side elevational view thereof; and

FIG. 5 is a bottom view thereof.

The broken line disclosure of a hand and logs in FIG. 1 is for illustrative purposes only and forms no part of the claimed design.
